UNITED STATES PATENT OFFICE.

OTTO KARTZMARK, OF NEW YORK, N. Y., ASSIGNOR TO THE UNITED STATES ELECTRIC LIGHTING COMPANY, OF SAME PLACE.

ELECTRIC-LAMP HOLDER.

SPECIFICATION forming part of Letters Patent No. 244,462, dated July 19, 1881.

Application filed March 8, 1881. (No model.)

To all whom it may concern:

Be it known that I, OTTO KARTZMARK, residing in the city, county, and State of New York, have invented certain Improvements in Electric-Lamp Holders; and I do hereby declare the following to be a full, clear, and exact description of the invention, such as will enable others skilled in the art to which it appertains to make and use the same, reference being had to the drawings accompanying and forming a part of the specification.

The object of my invention is to bring into one complete device a gas-burner and electric lamp, so that should it occur from any cause that the electric illuminating current is interrupted, or that the lamp, becoming injured or destroyed, is not easily replaced, another source of light may be ready at hand in the gas, which may be immediately turned on and lighted in the same bracket, or in any branch thereof, without delay, and without the necessity of altering any of its parts.

To this end I have devised a novel combination of the following elements: a gas-burner and bracket, an electric-lamp socket and spring circuit-breaker specially adapted thereto, and an electric lamp so arranged that either the electric current or the gas may be used at will as the source of light. These several instrumentalities I have illustrated in combination in the accompanying drawings, in which—

Figure 1 represents the complete device, embracing all the above-named parts. Fig. 2 is a view, partly in section, of a detached portion of the base; and Figs. 3, 4, and 5 are detached views of the operative portions of the spring circuit-breaking mechanism.

K is a cylindrical block, of non-conducting material, such as ebonite or hard rubber, the central portion of which is bored out to form a tube. At one end of K is inserted a circular block of metal, I, screw-threaded on its interior for attachment to the threaded end of a gas-pipe, N, and at the other a circular groove is cut to form a hub, over which fits, by screw-threads or otherwise, the tube L of an ordinary gas-burner.

B and E are two plates of resilient metal, attached to diametrically-opposite sides of block

K, and form, by the prolongations b e b' e', a 50 socket for an incandescent lamp. The plates B and E are completely insulated from each other, and each one is in electrical contact with one of the conductors C D of the lamp P, so that when the ends of the line-wires are connected with the said plates the current is completed through the lamps and the carbon conductor contained therein is heated to incandescence. The lamp to be used with this socket is of the usual pattern, the only points necessary to observe in its construction being that the interior supporting-neck, M, shall be of sufficient height and internal diameter to fit down over the tube L without touching the same at any point, and that the conducting-wires shall be carried down through the neck, close to the sides thereof, so that all danger of short-circuiting through the metal tube shall be avoided.

As a means of making and breaking the circuit in this device, I employ the following form of switch, which, it will be seen, is especially adapted thereto: In the side of block K a circular recess is cut, through which passes the shaft F of a switch, the bearings therefor being 70 at one end in the body of the block and at the other in the metal plate E. Passing freely through the shaft F, and at right angles thereto, is a pin, G, with rounded or beveled ends, its length being nearly equal to the internal diameter of the recess. In the groove in the upper part of block K a flat spring, J, of circular shape, is fastened by screws passing through the holes j' j' in its ends. The portion of the spring J directly over the switch, by being bent 75 as shown at j, Fig. 5, is carried down into the recess, so that it is compressed by the pin G when it is carried into a vertical position by shaft F. In a notch or depression in the wall of the recess, and directly beneath the shaft F, 80 is a conducting-strip, H, carried through the block K and uniting with the metallic nut I. The insulating-wall of the recess is cut away on one side of the strip H, forming the depression g, as shown in Fig. 4.

The operation of the switch is as follows: The circuit through the lamp is closed by turning the shaft F, which carries around with it

the pin G until the latter is brought in contact with pin H. The spring J, now being under compression by the position of the pin G, forces it firmly down on strip H, thus insuring a good electrical contact and completing the circuit from the metal plate E and shaft F through strip H, block I, to the gas-pipe or one of the line-wires, as the case may be. If the shaft be now slightly turned from left to right, the pin 5 working loosely therein is forced with a snap by the tension of spring J off from the strip H into the cut-away portion g, thus presenting the formation of an arc as the contact-points separate. As soon as brought into contact with 10 strip H in the depression h the pin G acts as a pawl and prevents the shaft from being turned backward. So, also, when freed from engagement with H it is driven by the force of the spring J into the cut-away portion g, which, as 15 shown in Fig. 4, is so formed that it is impossible to complete the circuit again, except by turning the shaft around through a half-revolution from left to right. Thus the contact-surfaces are kept always clean, and as the circuit 20 can only be broken by the snapping action of the spring the destructive effects of the voltaic arc which ordinarily occur in circuit-breakers are precluded.

The current for producing the light is preferably brought to the plate B by a wire attached to a hook, A. Its course from this 30 point is indicated by the arrows in Fig. 2, being through conductor C, to and through the lamp, and back to line by conductor D and the switch-35 connections.

This device may be used at will either as a gas-bracket or a holder for an electric lamp, and forms a useful adjunct to the introduction of the incandescent systems of lighting into 40 general use, as by means of it the ordinary gas-brackets may be utilized for supporting the lamps without impairing their utility for the original purpose for which they were designed.

45 Having thus illustrated and described the most improved manner of which I am at present aware of carrying out my invention, what I claim as new, and desire to secure by Letters Patent, is—

1. A combined gas-burner and electric-lamp 50 supporting base or socket adapted for attachment to and use with a gas pipe or bracket.

2. The combination of a gas-burner, an insulating electric-lamp base or socket, and an electric-circuit breaker with conductors, as 55 described, these parts being connected together and arranged for attachment to and use with a gas pipe or bracket.

3. In a combined electric-lamp holder and gas-burner, a perforated insulating base or 60 socket for an electric lamp, forming a prolongation of the gas-pipe, in combination with a burner or tube and metallic connections, leading from the line-wires, adapted to be put in connection with the terminals of an electric 65 lamp, whereby either the gas or an electric lamp may be employed as the source of light, as set forth.

4. The combination of gas-pipe N, electric-lamp base K, forming a prolongation thereof, 70 and provided with a burner, L, and conducting-plates B E, and an incandescent electric lamp adapted to fit down over the burner and complete the circuit between the contact-plates, as and for the purpose set forth.

5. The combination, in an electric-lamp base or socket for use with a metallic bracket, of the insulated cylindrical block K, plates B E, metallic nut I, inserted in the block K, and a switch, F, with conducting-strip H for making 80 and breaking the circuit between the plates and the nut, as shown.

6. In an electric-circuit breaker, a rotary shaft, F, and pin G, passing freely at right angles through the same, in combination with 85 a spring, J, and contact-strip H, constructed as described, these parts being arranged for operation, and contained within an inclosing case or recess of insulating material, substantially as hereinbefore set forth.

In testimony whereof I have hereunto set my hand this 7th day of March, 1881.

OTTO KARTZMARK.
